UNITED STATES PATENT OFFICE

TIMOTHY F. BLUDWORTH, OF SUMMIT, NEW JERSEY

REMOTE CONTROL SWITCH

Application filed December 22, 1927. Serial No. 241,878.

My invention relates to an improved switch and means for operating the same from one or more remote points. For example a specific application of my invention is to be found in connection with radio receiving apparatus in which it is desired to control the apparatus from a distance. It is desirable to place the loud speaker at a considerable distance from the main body 5 of the receiving apparatus in order to obtain the best results, and it is an object of my invention to provide means adjacent the loud speaker by which the receiving apparatus may be turned on or off. Furthermore, 10 by my invention it is possible to control the receiving apparatus from other points in the room in which the receiving set is located or from other rooms and more remote stations if so desired.

20 In this connection I would call attention to a copending application, Serial No. 168,381, filed Feb. 15, 1927, on a remote controlled switch, jointly invented by Igor S. Bobrovsky and myself, in which a magnetically actuated switch is provided for the remote control of electrical apparatus such as a radio receiving set. The present invention is an improvement on that described in said co-pending application in that it is 25 applicable to a standard switch and also in that it provides for a much greater throw of the switch than would be practicable with an electromagnet as the actuating means.

Thus it is an object of my invention to 30 provide simple means for operating a switch of standard make from a remote point.

Another object of the invention is to provide a very inexpensive switch actuating means which is not liable to get out of order 40 and which is operable with a very small amount of electric current.

Another object of the invention is to provide a switch controlling means which may be operated from a number of remote stations connected in parallel.

In said co-pending application the controlling means is so arranged that the switch would be alternately turned on and off by successive actuations. It is an object of the 50 present invention to provide a switch con-

trolling mechanism in which at the control station separate push buttons or equivalent means are provided for controlling the two positions of the switch so that the operator at the control station will have a positive 55 control of direction of actuation of the switch.

With these and other objects in view, my invention consists in certain novel features of construction and arrangements of parts 60 which will be described in connection with the accompanying drawings illustrating a preferred embodiment of my invention, and the scope of my invention will be clearly defined in the appended claims.

Referring to the drawings,

Fig. 1 is a diagrammatic view illustrating certain electrical connections used in my improved remote control switch, and

Fig. 2 is a somewhat diagrammatic view 70 of my improved switch and means for operating the same.

Referring more particularly to Fig. 2 I have shown at 10 a main switch from which projects a switch handle 11. The switch 75 is preferably of the tumbler type, although obviously other forms of switches could be used so long as they are operable by swinging the switch handle through a predetermined angle. The construction of the main 80 body of the switch forms no part of my invention and needs no specific description. Suffice it to say that with the handle 11 in one extreme position the switch will be turned on and with the handle in the other 85 extreme position, the switch will be turned off; or if desired, swinging the handle 11 in one direction, will close the circuit through certain contacts and swinging the handle in the other direction will close a 90 circuit through other contacts.

Secured to the handle 11 by any suitable means is a spring metal blade 12 which is preferably aligned with the handle. Mounted adjacent the main switch 10 is an electric 95 motor 13 which preferably drives a fly wheel 14. Secured to the fly wheel by means of a nut 15 on the fly wheel shaft 16 is an arm 17 which carries near its outer end a pin 18. The orbit of the pin lies in the 100

plane of movement of the blade 12 and the relation of the handle 11 to the arm 17 is such that throughout the angular movement of the handle 11 the blade 12 intersects the orbit of the pin 18. As the arm 17 revolves the pin 18 engages the blade and throws the switch and when the switch handle reaches the limit of its throw the blade 12, being of spring metal, will yield and permit the pin to snap past. As shown in Fig. 2, if the arm 17 rotates clockwise the pin 18 on striking the blade 12 will bend the blade clear of its path at each revolution. If, now the arm 17 be rotated counter-clockwise, or in the direction indicated by the arrow, the pin 18 will strike the opposite face of the blade 12 and will swing the switch handle 11 to the position indicated by broken lines. Continued rotation of the arm 17 in the same direction will result merely in flexing the spring and permitting the pin 18 to snap past the blade at each revolution. Thus by operating the motor to turn in one direction or the other, the switch handle 11 will be correspondingly operated.

The motor 13 is preferably a reversible series-wound motor which will operate equally as well on alternating current and direct current. In Fig. 1 the field 19 of the motor is shown as divided, one end being connected to a terminal point 20 and the other end to a terminal point 21 by means of leads 22 and 23 respectively. A lead 24 connects a median point of the field with a brush 25 running on the commutator 26. The other brush 27 is connected by a line 28 to one terminal of a suitable source of power, not shown. The other terminal of said source of power is connected by a line 29 to a pair of local switch levers or push buttons 30 and 31 which are adapted to coat with the contact points 20 and 21 respectively. Thus when the local switch 31 is operated to close the circuit through the line 23 the motor will run in one direction and when the local switch 30 is operated to close the circuit through line 22 the motor will run in the opposite direction. Obviously the switches 30 and 31 may be of any suitable form but they are preferably held open by means of springs 32 and 33 respectively. Thus normally no current flows through the motor 13 except when one of the push buttons is operated.

Only a momentary impulse of current is necessary to throw the main switch. By providing a fly wheel 14 on the power shaft of the motor sufficient energy is stored in the fly wheel to insure operation of the arm 17 even when a very short impulse of current is passed through the motor. However, if an operator should hold down a push button for a considerable length of time no harm would result because the arm 17 would merely continue to rotate and the pin

18, after throwing the blade 12, would merely spring the blade 12 and snap past it at each rotation.

Obviously a set of push buttons could be provided at a number of different control stations by connecting them in parallel with the push buttons 30 and 31. Thus in Fig. 1 I have shown a second set of push buttons 30' and 31' connected to the line 29 and adapted when operated to engage contact points 20' and 21' connected respectively to the leads 22 and 23.

Instead of connecting the fly wheel 14 directly to the power shaft of the motor it would be desirable in some instances to provide reduction gearing between the motor and the fly wheel whereby a very small motor of high speed could be utilized to operate the arm 17 at a comparatively low speed, the power being thus stepped up sufficiently to throw a large and heavy main switch.

While I have referred to my invention as specifically applicable for use in connection with radio receiving apparatus my invention is not limited to such application but obviously could be employed in connection with any other form of apparatus which it was desirable to control from a distance. For instance a valve could be substituted for the switch 10, and the term "switch" as herein used is intended to cover any device for cutting off or controlling the flow of any form of energy or any form of fluid. Furthermore my invention is not limited to the specific details of construction shown in the accompanying drawings and I reserve the right to make such alterations, variations and modifications of construction and arrangements of parts as fall within the spirit and scope of the following claims.

I claim:

1. In a control switch, a driving member, a driven member reciprocable between limits in the path of the driving member, one of said members being formed with a spring providing a yieldable engagement of the two members and permitting disengagement of the two members when the driven member has been moved to either limit of reciprocation, and an actuating means for propelling the driving member.

2. In a control switch, a driving member, a reversible motor for revolving the driving member, and a driven member reciprocable between limits in the path of the driving member, the driven member including a spring adapted to provide yielding engagement with the driving member and to permit disengagement from the driving member when the driven member reaches either limit of its reciprocation.

3. In a control switch, a revolvable driving member, a driven member mounted to swing through a limited angle in the path of the

driving member, said driven member including a blade of spring metal adapted to effect driving engagement between the driving and driven members and yielding at either 5 limit of movement of the driven member to permit disengagement of the driving member, and a reversible electric motor for revolving the driving member.

4. In a control switch a reversible motor, 10 a fly wheel driven thereby, an arm carried by the fly wheel, a pin on the free end of the arm, a switch lever, and a flexible blade carried thereby, the switch lever being mounted to swing through a limited angle 15 with the blade intersecting the orbit of said pin, said blade being adapted to yield when the switch lever reaches either limit of its swing to permit passage of the pin.

5. A switch comprising a driven member 20 reciprocable within predetermined limits and a reversible driving member capable of greater movement than the driven member, the latter having a spring arm extending across the path of the driving member 25 and providing a driving connection between the two members, said arm being adapted to be sprung out of the path of the driving member to break said connection when the driven member reaches either limit of its 30 reciprocation and to return immediately across said path so as to be engaged by the driving member upon the next succeeding stroke of the latter.
